Primary Examiner — Michelle E. Wilson*Assistant Examiner* — Sanjeev Paul(74) *Attorney, Agent, or Firm* — Werschulz Patent Law, LLC; Patricia P. Werschulz, Esq.(57) **CLAIM**

The ornamental design for a T-shirt shape bed sheet, as shown and described.

DESCRIPTION

FIG. 1 is a perspective view of a first embodiment of a T-shirt shape bed sheet in full lines covering a mattress, showing my new design; a nonspecific team symbol shown in broken lines, representing environmental association matter being for illustrative purposes only and forming no part of the claimed design;

FIG. 2 is a top plan view thereof, the nonspecific team symbol shown in broken lines;

FIG. 3 is a bottom plan view thereof;

FIG. 4 is a left side elevational view thereof;

FIG. 5 is a right side elevational view thereof;

FIG. 6 is a front elevational view thereof; and,

FIG. 7 is a rear elevational view thereof.

The broken lines shown in the drawings are included for the purpose of illustrating portions of the T-shirt shape bed sheet that form no part of the claimed design.

1 Claim, 4 Drawing Sheets(56)
